UNITED STATES PATENT OFFICE.

WILLIAM H. WEBER, OF FERNDALE, MICHIGAN.

ELECTRIC-IRON-CORD SUPPORT.

Application filed May 19, 1924. Serial No. 714,260.

To all whom it may concern:

Be it known that I, WILLIAM H. WEBER, a citizen of the United States, residing at Ferndale, in the county of Oakland and 5 State of Michigan, have invented certain new and useful Improvements in Electric-Iron-Cord Supports, of which the following is a specification, reference being had therein to the accompanying drawings.

10 This invention relates to a folding or swingable support for the cord or electric supply conductors of an electric flat iron or other device adapted to be manipulated relative to an ironing board, table or other 15 support, and my invention aims to provide a yieldable upright over which may be trained an electric flat iron cord whereby the cord will be out of the way of articles being ironed and also not interfere with manipulation of the flat iron. The yieldable upright is constructed so that it may be maintained in a folded or inactive position at one 20 edge of an ironing board or table and for this purpose the ends of the yieldable upright are constructed to facilitate supporting the upright in parallelism with an edge 25 of the ironing board or table. One end of the yieldable upright has a configuration for gripping the edge of the ironing board or table and the opposite end of the upright 30 is designed to be held by a bracket attached to the edge of the ironing board or table.

The construction entering into my invention will be hereinafter specifically 35 described and then claimed, and reference will now be had to the drawing wherein—

Figure 1 is a front elevation of the cord support, relative to an ironing board and electric iron;

40 Fig. 2 is an end view of the support;

Fig. 3 is a bottom plan of one end of the support;

Fig. 4 is a side elevation of a portion of the support;

45 Fig. 5 is a plan of the same, and

Fig. 6 is a perspective view of the outer end of the support engaging an ironing board.

The reference numeral 1 denotes an angle 50 bracket which is attached to the lower face of an ironing board 2 by screws 3 or other fastening means and said angle bracket has a vertical portion 4 provided with a lip 5 having a central notch or recess 6.

Mounted in the vertical portion 4 of the 55 angle bracket 1 is a screw 7 and adjustable on said screw is a wing thumb nut 8.

On the screw 7 between the nut 8 and the vertical portion 4 of the bracket 1 is an eye 9 of a yieldable upright 10 preferably made 60 of a semi-rigid wire or rod that is non-corrodable. The upright 10 is adapted to engage in the notch or recess 6 of the lip 5 and be clamped therein by the nut 8 holding the eye 9 against the vertical portion 4 of 65 the angle bracket 1.

The upper or outer end of the yieldable upright 10 has a return bend portion 11 terminating in a hook member 12 which cooperates with the return bend portion 11 in 70 forming a channel gripping member disposed substantially at a right angle to the upright 10.

With the upright 10 in an active position, 75 as shown in Fig. 1, a cord or conductor 13 can be suitably trained over the upper or outer end of the upright and it may be preferable to wrap the cord once or twice about the hook member 12 or place the cord in the return portion 11 so that the cord cannot accidentally shift or become displaced. Connecting the rod 13 to the upper end of the upright 10 is determined after ascertaining the travel of an electric iron 14 on the ironing board 2, it being preferable to allow sufficient slack in the cord 13, between the upright 10 and the iron 14, so that said iron can be freely manipulated on the ironing board. Should the iron be moved a greater distance than usual the upright 10 will 90 yield, bending over sufficient to prevent the cord 13 from being injured, displaced or the usual plug pulled from the iron.

Removing the cord 13 from the upright 95 10 and loosening the nut 8 permits of the lower end of the upright being shifted out of the nut 6 and the upright swung to approximately a horizontal position. The outer end of the upright can then be placed in engagement with the edge of the ironing board and if the ironing board is of the usual thickness the return bend portion 11 and the hook member 12 will cooperate in gripping the edge of the ironing board to 100 retain the outer end of the upright in engagement with the ironing board. The nut 8 can then be tightened against the eye 9 of the upright and the support will be firmly 105

held in engagement with the ironing board so as to be convenient the next time the board is to be used.

What I claim is:—

- 5 1. A support for the cord of an electric iron adapted to be manipulated on an ironing board or the like, comprising an angle bracket having a notch, a nut equipped screw carried by said angle bracket, a yield-
10 able upright having an eye end on said screw adapted to be held by the nut thereof with the upright in a notch of the angle bracket, said yieldable upright having its outer end of such configuration as to permit
15 of a cord being temporarily attached thereto and to permit of the outer end of the upright gripping the edge of the ironing board to co-operate with the bracket and

screw in supporting the yieldable upright substantially parallel to the edge of the iron- 20
ing board.

2. A support for the cord of an electric iron adapted to be manipulated relative to an ironing board or the like, said support comprising a yieldable upright having its 25 outer end bent either for supporting the iron cord or for gripping the edge of the ironing board, and means adapted for connecting the inner end of the yieldable upright to the ironing board.

In testimony whereof I affix my signature in the presence of two witnesses.

WILLIAM H. WEBER.
